DESIGN FOR A COMBINED SALT AND PEPPER SHAKER

Howard L. Ross, New York, N. Y.

Application February 26, 1943, Serial No. 109,632

Term of patent 7 years

To all whom it may concern:

Be it known that I, Howard L. Ross, a citizen of the United States, residing at New York city, in the county and State of New York, have invented a new, original, and ornamental Design for a Combined Salt and Pepper Shaker, of which the following is a specification, reference being had to the accompanying drawing, forming part thereof.

Fig. 1 is a perspective view of a combined salt and pepper shaker, showing my design;

Fig. 2 is a front elevational view with the pepper shaker element removed therefrom;

Fig. 3 is a rear elevational view thereof;

Fig. 4 is a front elevational view of the pepper shaker element as it appears when removed from the remainder of the article; and

Fig. 5 is a perspective view thereof.

I claim:

The ornamental design for a combined salt and pepper shaker, substantially as shown.

HOWARD L. ROSS.
